UNITED STATES PATENT OFFICE.

JOHN P. LEIN, OF NEW YORK, N. Y.

BEDSTEAD.

SPECIFICATION forming part of Letters Patent No. 746,852, dated December 15, 1903.

Application filed November 17, 1902. Serial No. 131,617. (No model.)

To all whom it may concern:

Be it known that I, JOHN P. LEIN, a citizen of the United States, residing at New York, in the county of New York and State of New York, have invented certain new and useful Improvements in Bedsteads, of which the following is a full, clear, and exact specification.

This invention relates to improvements in bedsteads, and has for its object to provide a construction which will permit the mattress-frame of a bed to be removed entirely or to be adjusted to various heights. In hospitals particularly it is often found desirable to treat a patient without removing him from the bed or to have the bed inclined or to raise the patient higher, so as to obviate the necessity of bending over to attend to him.

With these objects in view I have devised the construction which I will now more particularly describe.

In the drawings, Figure 1 is a side view of one end of a bed, showing the mattress-frame elevated. Fig. 2 is an end view of a bed-frame provided with my invention. Fig. 3 is a detail side elevation of a mattress-frame. Fig. 4 is a detail view of an end post of a bed, showing the rack supporting the corner of the mattress-frame; and Fig. 7 shows a rack cut in the bed-post. Fig. 5 is a plan, seen from below, of the frame shown in Fig. 3. Fig. 6 is a modification of Fig. 5.

I provide each of the four posts 1 of a bed with racks 2. Fig. 2 shows the arrangement and location of the racks on one end of the bed, the arrangement for the other end being the same.

The mattress-frame is composed of angle-bars 3 4 and carries the woven-wire springs 8 in the usual manner. As ordinarily made this frame cannot be adjusted to different heights, nor can it be removed without great difficulty. Pivoted near each corner of the frame on the side bars are levers 6, normally pushed outward by springs 7. The levers 45 may be provided with suitable stops, as 12, to prevent them from moving out too far. By this construction the lever forms a rigid handle when pushed outward by binding against the angle-bar 4. The pivots 9 of the levers 50 are in slots 10, so that the levers can be moved bodily longitudinally of the side toward each other to permit them to clear the top bars of

the end frames of the bedstead when it is desired to remove the mattress-frame entirely. It will thus be seen that I am enabled to use 55 the mattress-frame as a stretcher, which is found to be of great convenience in hospitals, the levers 6 serving as handles. The racks 2 enable the frame to be adjusted to various heights and also permit one end to be at a different height from the other.

When it is desired to change the position of the mattress-frame, an attendant at each end of the bed grasps the two levers of the frame at each end and presses them inward 65 toward each other and then adjusts the mattress-frame as desired. The springs push the levers outward and cause them to engage the racks to sustain the mattress-frame.

In Fig. 6 is shown a modified construction 70 which enables the tension of the spring to be regulated. 14 is a bolt having a head 15 and a nut 16. 13 is a coiled spring which bears at one end on the head 15 and at the other on an eyebolt 17, which is adjustable in the 75 slot 16 to vary the tension of the spring. This can also be effected by screwing the nut 18.

I do not limit myself to the construction I have illustrated, as my invention can be applied to many other constructions by a skilled 80 mechanic.

Having thus described my invention, I declare that what I claim as new, and desire to secure by Letters Patent, is—

1. The combination with a bed-frame having notches, of a mattress-frame having a lever independently pivoted near each corner thereof and engaging the notches to support the mattress-frame at any desired height or angle, substantially as described. 85

2. The combination with a bed-frame, of a mattress-frame having levers slidably mounted near the corners thereof, and means for holding the levers in engagement with the bed-frame to support the mattress-frame, 95 substantially as described.

3. In a bed, a mattress-frame having a lever mounted on the side bars near each end thereof, means for holding the levers in engagement with the bed-frame, and means permitting the levers to be moved longitudinally 100 so as to clear the ends of the bed-frame.

4. In a bed, the combination with the corner-posts having each a rack thereon, of a

removable mattress-frame having a lever mounted near each corner thereof, and means causing the levers to engage the racks to support the ends of the mattress-frame independently, substantially as described.

5. The combination, in a bed, with corner-posts having racks thereon, of a mattress-frame having a spring-actuated lever slidably mounted near each end of the side bars, substantially as described.

6. In a bedstead, the combination with a bed-frame having supporting means, of a mattress-frame having coöperative spring-

controlled supporting means independently attached near each corner thereof and engaging the supporting means on the bed-frame, to permit the ends or sides of the mattress-frame to be independently adjusted to any desired height or angle, substantially as described.

In testimony whereof I affix my signature in presence of two witnesses.

JOHN P. LEIN.
